UNITED STATES PATENT OFFICE

2,588,658

METAL SCRIBING GAUGE

Louis Plotnik, Compton, Calif.

Application June 23, 1948, Serial No. 34,640

1 Claim. (Cl. 33—42)

1

My invention relates to gages particularly adapted, although not necessarily, for scribing guide lines on sheet metal incident to cutting the metal into various sizes and shapes.

It is a purpose of my invention to provide a gage for the above described use which is characterized by its structural simplicity, low cost of manufacture, durability, and easy mode of adjustment and operation to scribe a line in sheet metal at any predetermined distance from an edge thereof.

I will describe only one form of metal scribing gage embodying my invention and will then point out the novel features thereof in a claim.

In the accompanying drawings:

Fig. 1 is a view showing in perspective one form of metal scribing gage embodying my invention, in scribing position on a sheet of metal.

Fig. 2 is an enlarged view showing the gage in front elevation.

Fig. 3 is a view showing the gage in rear elevation.

Fig. 4 is a vertical sectional view taken on the line 4—4 of Fig. 3.

Fig. 5 is a sectional view taken on the line 5—5 of Fig. 3.

Having specific reference to the drawings, my invention in its present embodiment comprises an elongated flat body B of suitable width and length to be easily held in the hand, and preferably constructed from a single sheet of metal of relatively heavy gage so that in normal use it will maintain its true linear form to slidably hold a ruler R.

Integral with the longitudinal edges of the body B are flanges 15 and 16, bent to one side of the body and coacting to stiffen the body and form a channel for slidably receiving the ruler R. As will be noted the flange 15 is coextensive in length with the upper edge of the body, but the flange 16 terminates short of the forward end of the lower edge of the body where, the body edge is formed with an integral extension 17 in the plane of the body and shaped to provide an abutment with a straight edge 18.

The ruler R of my gage comprises a flat strip of metal of relatively heavy gage to prevent bending or flexing in its normal use, and of such width as to be slidable in the channel formed by the flanges 15 and 16, and hence adjustable longitudinally on the body B. The ruler on its outer side is provided along its lower longitudinal edge and at right angles thereto with graduations 19 in inches and fractions thereof.

The zero graduation (see Fig. 3) is at the for-

2

ward end of the ruler R where, the ruler is provided with an integral extension 20 which is bent upon itself to form a sleeve 21. Prior to the formation of this sleeve a scribing instrument 22 in the form of a steel needle, is positioned so that when bending the metal the needle is firmly clamped in the sleeve and thus permanently held thereon.

It will be noted that the sleeve 21 is at an acute angle to the lower edge of the ruler to hold the needle 22 in such position that its point 22a is on a straight line projected from the zero graduation. This is in order that the line scribed on a sheet of metal by the needle can be accurately measured by the ruler in relation to an edge of the metal sheet.

For securing the ruler R in any position of adjustment longitudinally in the body B, and hence, the needle 22 in various spaced positions in relation to the straight edge 18 of the abutment 17, a simple and effective clamping device D is provided, additionally characterized by the fact that it can be operated to secure or release the ruler by a single finger of the user.

This clamping device may comprise a pair of ears 23 formed on the back of the body B by outstriking and shaping portions of the metal, and leaving an opening 24 in the body between the ears. A lever 25 is fulcrumed on the ears 23 by a pin 26, and a pair of cams 27 are formed on the lever at points to be extendible through the opening 24 to engage the ruler R. On the free end of the lever a winged-shape handle 28 is formed to be engaged by the finger of the user for actuating the lever to release the ruler, when it is in the ruler-clamping position shown in Fig. 1.

In the use of my gage, the ruler is first released by swinging the lever 25 from the solid line position to the broken line position shown in Fig. 4, whereupon by moving the ruler in one direction or the other longitudinally in the body B, it can be adjusted to space the needle 22 any desired distance from the straight edge 18 as indicated by the graduations 19.

Once the desired adjustment of the ruler has been made, the user swings the lever 25 to the solid line position shown in Fig. 4, thus turning the cams 27 past the dead center position to force and hold them against the side of the ruler and thus lock the latter against movement in the body. Thus the gage is now ready for application to a sheet of metal L as illustrated in Fig. 1.

55 By holding the gage in the manner shown, and

bringing the straight edge 18 into engagement with the edge of the sheet and the needle point 22a into contact with the surface of the sheet, a line can be scribed on the sheet through movement of the gage along the sheet. By maintaining the straight edge firmly against and perpendicular to the sheet edge, the line scribed by the needle will be in parallelism with the sheet edge and thus a definite distance from such edge as predetermined by the prior adjustment of the ruler.

Although I have herein shown and described only one form of metal scribing gage embodying my invention, it is to be understood that various changes and modifications may be made therein without departing from the spirit of my invention and the spirit and scope of the appended claim.

I claim:

A flat metal scribing gage, including: an elongated body of sheet metal provided with bent-over top and bottom flanges substantially co-extensive in length therewith, and providing guide channels at one side thereof, the bottom flange terminating short of the end of the body and having a portion extending outwardly to lie in the plane of the body and providing a straight edge with the end of the body; a flat metal ruler slidable longitudinally in said channels and provided along its lower edge with scale markings adapted to be brought into registration with the straight edge from zero marking to the end marking of the scale; an integral extension on the operative end of said ruler bent upon itself to provide a sleeve for holding a scribing needle therein; said body at a point adjacent the

straight edge being outstruck at its back to form outwardly projecting ears and an opening between the latter in which the back of said ruler is exposed; and a lever of U-form in cross section having its parallel portions fulcrumed in said ears and formed at their fulcrumed ends into a pair of space cams which, in one position of the lever engage the back of the ruler for locking it in any position of adjustment longitudinally in the body, and in another position disengage the ruler, the lever of a length that in ruler-locking position its free end projects above the upper edge of said body so that the lever is movable to operate the cams by a finger of the hand in which the gage is held.

LOUIS PLOTNIK.
